UNITED STATES PATENT OFFICE

2,568,657

FURNACE GRATE STRUCTURE, INCLUDING
ASH REMOVAL MEANS

William F. Pfau, Norwood, Ohio

Application December 15, 1947, Serial No. 791,859

4 Claims. (Cl. 110—36)

1

This invention relates to a novel and improved combustion device in which solid fuels, such as coal, coke or the like, are burned in heating and cooking stoves, boilers or furnaces, more particularly of the types used in small homes and dwellings. The improved device provides an efficient combustion chamber to which the fuel is fed to be completely burned, and the ash residue is removed in an even and uniform flow in continuity with the flow of the fuel through the combustion chamber.

The invention pertains particularly to a circular grate formed from several superposed circular rings disposed to provide a combustion chamber above an oscillating plate which serves as the bottom for the combustion chamber. Lever arms are provided on the top of the oscillating plate to be manipulated relatively to the plate whereby the ash residue is removed continually from the bottom of the combustion chamber and over the edge of the plate where it can be collected and removed. The lever arms form a U-shaped pocket or chamber in the bottom of the combustion chamber, and, when oscillated relatively to and with the plate, they continually push the ash residue out of the open side of the U-shaped pocket or chamber to an ash receptacle or remover.

For a better understanding of the invention, reference is made to the accompanying drawings in which:

Fig. 1 is a vertical cross-sectional view of the device embodying the invention.

Fig. 2 is a horizontal cross-section on line 2—2 of Fig. 1.

Referring to the drawings in which like numerals are used to designate like parts, numeral 1 is a base or foundation of a furnace bowl 2 of conventional design. A refractory ring 3 is supported on a ledge 4, preferably integral with the bowl, in the furnace above a grate composed of grate rings 5 with the bore of the refractory ring registering with the bore of the grate rings. There are any number of superposed grate rings to build up a fire box or combustion chamber of any desired depth. Knobs 5a may be formed at spaced intervals on the top or bottom edges of the grate rings to contact with the adjacent rings to provide air spaces therebetween. The grate rings are supported by means of any number of legs or brackets 5b which are attached to some fixed part of the furnace, such as wall 6 or the base 1, or the bottom ends of the brackets or legs may be fixed to the plate 7 as shown. When the legs or brackets are fixed to some fixed

2

part of the furnace, such as base 1 or side wall 6, the grate rings are supported entirely independently of the plate 7, and this facilitates insertion and removal of the oscillating plate unit. However, when the legs or brackets are fixed to the plate 7, the grate rings will be oscillated with the plate to further agitate the contents of the combustion chamber. About three or more of these legs or brackets, spaced apart, are sufficient for supporting the grate rings.

The plate 7 is movably mounted upon the base or foundation 1 by means of a bearing unit 8, preferably an anti-friction one, interposed between the foundation and the plate. This bearing may be any conventional roller or ball bearing with the rollers or balls 8a interposed between two raceways 8b. A center stud 9 is advantageously provided, if desired, as a pivot for holding the plate 7 centered, although the bearing alone may suffice to keep the plate centered, particularly if the raceways be fixed respectively to the base and the plate as they may be by spot welding. The stud can be fixed either to the foundation or the plate by any suitable means such as welding, and is of a diameter to fit the bore of the raceway rings of the bearing.

Two arms 10 are each pivoted to the top side of the plate 7 by means of a stud shaft 11 fixed to the plate. The arms are duplicates, and are oppositely disposed with the curved ends 12 abutting and the main portions of the arms parallel. The inside edge surfaces 13 of the curved ends are arcuate, and, with the main portions of the arms, they form a U-shaped member on the top of the plate to provide a U-shaped pocket or chamber for the bottom of the combustion chamber. The ends of the arms opposite to the curved ends are pivoted at 14 to a cross piece 15 which in turn is pivoted at 16 to a cross support 17. The ends 18 of the cross support may be fastened to the furnace wall 6 by any suitable means, such as bolts 19. This cross support thus firmly holds the plate unit in position.

The arms, as well as the plate to which they are pivoted, are oscillated by a prime mover, such as motor 20, which is attached to the arms by any suitable power transmission mechanism. This mechanism may advantageously be a link 21 pivoted at one end to the cross piece 15 or to one of the arms at 14 as shown. The link is pivoted at the other end by stud 23 on a cam 24 which is attached to the motor shaft.

As the arms are oscillated from the full to the dotted line positions, their arcuate inner edges will work the ash residue towards the opposite

side of the plate and over its edge where it gravitates to an ash remover 25, the ash remover being typified by a screw conveyor.

In order to prevent any ashes working between the curved ends of the arms, their outer end surfaces 26 are diverged to provide a triangular area which can be partially or completely filled by a triangular piece 27 which is attached to the upper surface of the plate.

A front door 28 can be provided as shown in the wall of the bowl of the furnace to permit the unit being inserted in and removed from the furnace. The door can have an air draft regulator of conventional construction for letting in or shutting out the air.

The furnace may be hand fired or mechanically fired with a screw conveyor 29 disposed to discharge a supply of fuel into the furnace at the top of the combustion chamber. If mechanically fired, the necessary automatic thermostat controls may be used, but these are, of course, conventional, and may be used or not, as desired.

The device is simple in construction and may be readily installed as a unit in any conventional coal-burning furnace. It lends itself to hand or mechanical firing and moves the coal evenly through the combustion chamber where all parts are exposed to air mixture so that combustion will be complete. As the ash residue is removed, the fuel in the combustion chamber is slightly agitated and is moved uniformly towards the U-shaped chamber in the bottom where the ash residue is also uniformly removed to an ash container or collector.

While I have illustrated and described one preferred embodiment for carrying the invention into effect, it will be understood that there may be various changes in details of construction without departing from the spirit of the invention.

I claim:

1. A combustion device for burning solid fuels comprising a fire box forming a combustion chamber, a plate beneath the fire box and disposed horizontally for supporting the solid fuel thereon, a bearing for movably supporting the plate, a lever arm pivoted intermediate its length to the plate for moving relatively to said plate and having a terminal portion extending horizontally adjacent the top surface of the plate, and means for moving the plate and lever arm relatively to each other for causing the terminal portion of the lever arm to push the material in

the bottom of the combustion chamber over the surface of the plate.

2. A combustion device for burning solid fuels comprising a fire box forming a combustion chamber, a plate beneath the fire box and disposed horizontally for supporting the solid fuel thereon, a bearing for movably supporting the plate, a pair of lever arms having curved ends and pivoted intermediate their length to the margin of the plate in spaced apart relation with the curved ends of the lever arms adjacent each other to form a U-shaped wall in the bottom of the combustion chamber around the top surface of said plate, and means for oscillating the plate and lever arms for causing said lever arms to push the contents of the bottom of the combustion chamber out of the U-shaped opening resulting from the U-shaped wall.

3. A combustion device for burning solid fuels comprising a fire box forming a combustion chamber, a plate movably mounted beneath the fire box, a pair of lever arms having curved ends and pivoted intermediate their length to the plate in spaced relation with the curved ends of the lever arms disposed adjacent each other to form a U-shaped pocket in the bottom of the combustion chamber above the plate, and means for oscillating the lever arms relatively to the plate for causing same to push the contents of the bottom of the combustion chamber out of the open end of the U-shaped pocket.

4. A combustion device for burning solid fuel comprising a fire box forming a combustion chamber for burning the solid fuels, a movable horizontally disposed plate beneath the fire box for supporting the fuels in said fire box, a lever pivotally supported intermediate its length to said plate with one end thereof in position to be moved adjacent to the top surface of the plate for pushing the material within the fire box toward one edge of the plate.
